US00D657568S

(12) **United States Design Patent**
Jimenez et al.

(10) **Patent No.:** **US D657,568 S**
(45) **Date of Patent:** **** Apr. 17, 2012**

(54) **ORAL CARE IMPLEMENT**

(75) Inventors: **Eduardo Jimenez**, Manalapan, NJ (US); **John Gatzemeyer**, Hillsborough, NJ (US); **Robert Moskovich**, East Brunswick, NJ (US); **Alan Sorrentino**, Cranbury, NJ (US); **Alberto Mantilla**, Millburn, NJ (US); **Jason Liang**, Fresh Meadows, NY (US); **Lucas Wade**, Brooklyn, NY (US)

(73) Assignee: **Colgate-Palmolive Company**, New York, NY (US)

(**) Term: **14 Years**

(21) Appl. No.: **29/356,492**

(22) Filed: **Feb. 26, 2010**

(51) **LOC (9) Cl.** **04-02**

(52) **U.S. Cl.** **D4/108**

(58) **Field of Classification Search** D4/101, D4/104-112, 134, 138; D24/146, 147, 152; 15/110, 143.1, 167.1, 167.2; 132/308-311; 601/139, 141, 142; 606/161

See application file for complete search history.

(57) **CLAIM**

The ornamental design for an oral care implement, as shown and described.

DESCRIPTION

FIG. 1 is a right, front perspective view of an oral care implement showing our new design;

FIG. 2 is a left, front perspective view thereof;

FIG. 3 is a right, rear perspective view thereof;

FIG. 4 is a left, rear perspective view thereof;

FIG. 5 is a front elevation view thereof;

FIG. 6 is a rear elevation view thereof;

FIG. 7 is a right side elevation view thereof;

FIG. 8 is a left side elevation view thereof;

FIG. 9 is a top plan view thereof; and,

FIG. 10 is a bottom plan view thereof.

The broken lines showing cleaning elements illustrate portions of the oral care implement that form no part of the claimed design.

1 Claim, 5 Drawing Sheets
